UNITED STATES PATENT OFFICE.

EMMIT G. LATTA, OF SYRACUSE, NEW YORK, ASSIGNOR TO CORONA TYPEWRITER COMPANY, INC., A CORPORATION OF NEW YORK.

TYPE-WRITING MACHINE.

1,274,902.

Specification of Letters Patent.

Patented Aug. 6, 1918.

Original application filed November 2, 1911, Serial No. 658,153. Divided and this application filed June 10, 1918. Serial No. 102,934.

To all whom it may concern:

Be it known that I, EMMIT G. LATTA, a citizen of the United States, and a resident of Syracuse, county of Onondaga, and State of New York, have invented certain new and useful Improvements in Type-Writing Machines, of which the following is a full, clear, and exact description.

This invention relates more particularly to the escapement mechanism of visible, collapsible or foldable writing machines, and is a division of my application Serial No. 658,153, filed Nov. 2, 1911.

One of the principal objects of the invention is to provide a small, compact, visible writing typewriter which is adapted to perform all the functions required of the larger and more expensive typewriters of the most approved design, and which is so constructed that the escapement mechanism may be moved with the carriage from a normal operative position to a more compact one without any disconnection or separation of the parts forming the operative connection between said escapement mechanism and the universal bar.

Another object of the invention is to provide a simple and efficient rotary escapement for small foldable or collapsible typewriting machines.

Other objects of the invention are to provide a machine in which there is a complete separation between the type action and the universal bar and escapement mechanism operated thereby; to provide simple means whereby the universal bar may be operated by the type-bars and which universal bar is so mounted that it may be moved from a normal operative position to an inoperative compact one; to provide a separated operative connection between the universal bar and the spacing means; to provide simple spacing means for operating the universal bar; and to provide a simple and efficient non-separable escapement to adapt the machine to be made compact and to be moved from a normal operative position to a more compact one relatively to the type action.

A further object of the invention is to provide a simple and efficient escapement

which is very rapid in operation, and which is adapted for use for typewriters of various kinds and constructions.

A still further object of the invention is to provide a writing machine in which the escapement mechanism and other parts are of simple construction and may be readily made and assembled.

With these and other objects in view, the invention will be hereinafter more particularly described with reference to the accompanying drawings, which form a part of this application, and will then be pointed out in the claims at the end of the description.

In the drawings, Figure 1 is a longitudinal section, partly in elevation, of one form of machine embodying the invention.

Fig. 2 is a fragmentary section from front to rear of the machine, showing a part of the frame, the case shift mechanism, and the spacing mechanism for operating the universal bar.

Fig. 3 is a side elevation of the machine shown in a collapsed or compact condition.

Fig. 4 is a rear elevation of the escapement mechanism.

Fig. 5 is a fragmentary section, partly in elevation, of the universal bar, and means for operating the escapement.

Fig. 6 is a fragmentary section of a part of the means shown in Fig. 5.

Fig. 7 is a fragmentary plan, partly broken away, showing the universal bar and the frame and parts at one side of the machine.

Fig. 8 is a detail front elevation of the escapement mechanism and the universal bar connected thereto.

Fig. 9 is a fragmentary vertical section showing how the frames or frame parts are held in a collapsed or in an extended operative condition; and

Fig. 10 is a fragmentary plan, partly in section, of a part of the front of the machine, and is substantially a continuation of the side of the machine shown in Fig. 7.

While I have shown the invention as applied more particularly to a writing machine in which the parts are collapsed or

folded in a particular manner, it will be understood that some of the parts, and particularly the special construction of escape-
ment mechanism, may be used in connection
6 with various kinds of writing machines.

10 and 11 represent respectively the base
or stationary frame part or section of the
main frame and the movable frame part or
section. Each of these parts consists of a
14 rigid substantially rectangular frame, pro-
vided with suitable lugs or parts for the at-
tachment of the various operative parts
mounted thereon. The movable frame or
part is preferably larger than and surrounds
15 the stationary frame or part 10 and is piv-
otally connected thereto at its front end by
pivots at opposite sides of the machine.
One of the pivots 12 which may be of any
20 suitable construction, is shown in Figs. 3
and 10. The frames are connected at oppo-
site sides by a pair of coil springs 14, Figs.
3 and 7, which tend to raise and support the
movable frame in the elevated position
25 shown in Fig. 1. As shown, these springs
are hooked at their upper ends into lugs 15
projecting outwardly from the sides of the
stationary frame 10 and at their lower ends
are hooked into inwardly projecting lugs
30 on the sides of the movable frame or frame
part 11. These springs are preferably of
sufficient strength to hold the movable frame
with the parts mounted thereon in the ele-
vated operative position when permitted so
35 to do. 16 represents two thumb screws on
opposite sides of the machine which are
seated in studs 17 on the sides of the move-
able frame and are adapted to be screwed into
the sides of the stationary frame 10. The
40 studs 17 are rigidly seated in the sides of
the frame or frame part 11 and are pro-
vided at their inner ends with circular
flanges which engage and are adapted to
slide in curved guides or slots 18^a on the sides
45 of the stationary frame 10. These slots or
guides are concentric with the pivots for the
movable frame or frame member 11. When
the machine is shipped from the manufac-
turers, and when not in use the movable
50 frame or part 11 is secured in the lower po-
sition shown in Fig. 3 by screwing the thumb
screws into the lower holes 18. To make
ready for use it is only necessary to un-
screw the screws from the lower holes, when
55 the springs will raise the movable frame,
and then preferably screw the screws into
the upper holes 19. The springs will hold
the movable frame in its elevated position
and the machine can be used without in-
60 serting the screws into the upper holes 19,
but it is preferable to lock the frames or
frame parts 10 and 11 rigidly together by
the screws if the machine is to be used to
any considerable extent.

65 The paper carriage 20 is mounted to

travel horizontally crosswise of the machine
on the rear portion of the movable frame or
frame part 11. The carriage may be of any
suitable construction and may be slidably
70 mounted on the frame 11 in any suitable
manner. As shown the carriage consists of
opposite end pieces or plates 21 and 22 con-
nected at their front portion by a scale bar
23, at the rear by a rod or bar 24 and at the
75 bottom by a track or guide bar, consisting of
two sections 25 and 26. These track bar
sections are steel bars machined to the cross
sectional shape shown in Fig. 1 and are se-
cured to each other and to the ends of the
carriage by screws or otherwise, and the
80 overlapping portions of the track sections
are also secured together at intervals. A
grooved guide or track bar 27 is secured at
suitable intervals by screws, not shown, in a
recess in the rear cross bar 28 of the move-
85 able frame. This bar is machined to form
opposable ball races and the carriage track
bar extends into the grooved track bar 28,
suitable anti-friction balls being interposed
90 between the races in the bar 28 and comple-
mentary races formed in the front and rear
edges of the sectional carriage track bar.
This construction forms an anti-frictional
ball bearing guide for the carriage of very
95 compact construction which is required by
reason of the limited space allowed for the
carriage guide, and insures long life with
the minimum friction in the track bearing.
A platen 29 of the usual or of any suitable
100 construction is mounted in the carriage 20.
It consists of a hollow body provided with
a suitable surface or covering and secured
by end plates 30 to a central shaft 30^a which
extends through the platen and is jour-
naled at its ends in the ends of the carriage,
105 said carriage being normally under the ten-
sion of a spring drum 30^b mounted on the
movable frame part 11 and tending to force
the carriage along the track bar 27 in the
usual way.

A number of type-bars 31 are pivotally
mounted in any suitable manner in front of
and below the carriage on a supporting seg-
ment 32 mounted on the stationary frame
10. The type-bars are arranged to swing
115 upwardly and rearwardly to the platen and
each bar has three characters, the support-
ing segment being mounted on a shift frame
which is movable upwardly and downwardly
from an intermediate position for placing
120 one or another of the characters in printing
relation with the platen. The segment 32 is
shown as secured to a shift frame 33. One
case shift may be employed instead of two
125 in which case each type bar will have two
characters instead of three.

The key actions for the type-bars, may be
formed of sheet metal stampings. The key
stems 34, 35 and 36 as clearly shown in Fig.
1, are made in three different forms for the
130

three banks of keys and have downwardly extending portions pierced for shouldered rivets by which they are pivoted to the front ends of supporting levers 37 and 38, each stem being pivoted to a pair of the levers. These levers 37 and 38 are pivotally mounted, preferably in slots in the upper and lower edges of a fulcrum bar 39 which is rigidly connected at its ends in any suitable manner to the sides of the stationary frame. The rear ends of the key levers 37 and 38 are connected by links 40 and 41 which are of two forms, as shown in Fig. 1. Certain of the key levers, preferably four at each end 15 of the keyboard, are connected by the links 40 and all of the remaining levers of the series are connected by the links 41. The links 40 used at the ends of the keyboard are made of different shapes than the other 20 links, so as not to interfere with other parts of the machine at the sides thereof. The links 40 and 41 are connected to their respective type-bars by long links 42, two of which are shown in Fig. 7. These links 42 are all of the same length and embrace the parts to which they are pivotally connected at their ends. The links 42 at the center of the series are curved, as shown in Fig. 1, so as not to strike the type-bar basket when 25 the segment is in its lower shifted position, but the remaining links may be straight, if desired. The links 40 are made alike, each with four rivet holes, so that this form of link can be used for either of eight different 30 places, but as there is very little difference in the elevation of the front ends of the links 42 where they connect to the links 41, there is not sufficient room to make these links with rivet holes for all connections 35 with the links 42. The links 41 are made with the lowermost holes, and the other holes required for connection to the several links 42 are made at the proper points in the several links. The type-bars and key- 40 actions are returned to the normal positions by springs 43 and 44 which are attached to the lower key-levers 38 and to the front bar of the frame 10, as by the heads of screws acting as clamps. The springs with one exception as 44 are secured to the under side of the front bar of the stationary frame, the spring 44 being secured to the upper side of the bar to make room to actuate one of the center actions.

45 It will be observed that the keys 45 for the three banks are all connected to the levers 37 and 38 which are fulcrumed on the bar 39. This bar with the two fulcrum wires 46 for the levers extends the full length of the keyboard and is the only part of the key action that requires machining. This bar, as hereafter explained, also supports the space key, and as the other parts may all be stampings, the complete action 50 can be made at a low cost. Except for a

few of the links at the center of the series, the links 42 diverge forwardly from the type-bars owing to the greater length of the keyboard than of the segment, and the links 40 and 41 are indicated as bent in rear of 70 the key-levers 37 and 38, to extend in the direction of the links 42. The same result of a direct pull on the links 42 could be obtained by bending the supporting key-operated levers 37 and 38 in rear of their fulcrums. This action as a whole is unusually 75 easy to operate, its touch and dip are almost exactly uniform for the several keys, and it enables the segment to be located very low in the machine so that the rear ends of 80 the links 42 barely clear the table on which the machine is used, the action thus materially assisting in reducing the height of the machine. The keys are arranged in banks or groups and form a universal or 85 standard keyboard, and each type-bar is operated by an individual key.

The shift frame 33 to which the type-bar segment is secured, is provided with forwardly and outwardly projecting arms 47 90 having upright front portions which are pivoted at their upper ends in any suitable manner to the rear ends of a pair of supporting links 48, and are pivoted in any suitable manner at their lower ends to the 95 rear ends of a pair of supporting arms 49. The links 48 are pivotally mounted at their front ends in any convenient way to lugs 50 on the stationary frame 10 and the arms 49 are rigidly attached at their front ends 100 to a rock shaft 51. This rock shaft is suitably journaled at its ends in the sides of the stationary frame or frame part 10 and the central part of the rock shaft is curved 105 downwardly to clear the central connecting links 42 for the type-bars.

52 and 53 represent two shift levers. These shift levers, which are of bell crank form, are preferably pivoted side by side on a pivot screw 54 on one side of the frame 10. The lower ends of these levers, see Figs. 1 and 2 are provided with curved cam slots 55 and 56 acting on a roller 57 suitably journaled on the adjacent side of the shift frame to move it up or down from its normal intermediate position shown in the drawings. The shift levers are returned after movement up or down to the intermediate position by springs 58 which are connected to the shift levers and are anchored 110 to their front ends by adjusting eye bolts to the lug 59. The lug 59 limits the return of the shift levers to the same normal position. As seen in Fig. 2, each cam slot acts to move the roller a certain distance in one 115 direction and to form a stop to hold it in normal position and prevent its movement in the opposite direction, and the springs 58 actuate the cam levers to restore the roller and the shift frame to their central 120 125 130 135 140 145 150 155 160 165 170 175 180

positions when the levers are released. The weight of the shift frame is preferably balanced by a spring, not shown.

59 represents the type-bar basket or back stop for the type-bars, consisting of a curved metal strap and felt pad which is supported at its ends by arms 60 which extend backwardly and outwardly and are connected to the upright portions of the arms of the shift frame.

The universal bar 61 is arranged to be struck by the type-bars as they approach the platen and, as usual, is connected to the carriage escapement, so as to cause a letter 15 space movement of the carriage each time a type-bar is actuated to make an impression. The universal bar consists of a curved strip having two parallel rigidly connected rearwardly extending arms 62 which are pivoted 20 to the lower ends of two pairs of downwardly extending arms 63 and 64. These arms are rigidly attached at their upper ends, to the ends of a pair of parallel rock shafts 65 and 66 respectively which are suitably journaled to lugs on a bracket 67, the latter being secured in any suitable manner to the rear cross bar 28 of the movable frame or part 11. One of the arms 64, see Figs. 5 and 6, has an auxiliary arm 68 pivoted thereto and extending rearwardly to a pivotal connection with an upright link 69 which is connected at its upper end to the escapement lever or dog carrier 70 of a carriage escapement 71, so that the escapement 35 is actuated by the operation of the universal bar. A spring 71 connected to the arm 64 and to the bracket 67 acts to hold the universal bar yieldingly in its normal position. The universal bar is arranged above and 40 substantially concentric with the type-bar segment in position to be struck by the type-bars in each of the three positions of the segment. The type-bars strike the universal bar near their longitudinal centers. The 45 curved front edge of the universal bar stands in a plane parallel with the type-bar segment and those parts of the type-bars which strike the universal bar are in a parallel plane at the time they reach the printing point. This construction not only permits of the compact build of the typewriter required, but produces a quick action of the universal bar and provides a construction in which the wear is distributed between three 50 different points on both the type-bars and the universal bar.

72 represents the space key or bar which, as usual is arranged at the front central portion of the keyboard and may be fixed to three arms 73, see Figs. 1 and 2 which are pivoted on the fulcrum bar 39 by the upper wire pivot 46 for the key-levers. A lever 74, Fig. 2, fulcrumed on the lower pivot wire 46 for the key-levers is connected by a link 75 65 to the central arm 73. A spring 76 con-

nnecting the outer end of the lever 74 to the inner end of the arm 73 serves to hold the space key in its normal position and return it to this position when released after depression. An upright space lever 77, Fig. 2, 70 is pivoted between its ends on a bracket secured to the center of the type-bar segment. The lower end of this lever is connected by a link or rod 78 to the rear end of the lever 74 and the upper end of the lever 74 normally stands just in front of the universal bar 61 and extends high enough to strike the universal bar in all three positions of the shift frame and segment. The act of depressing the space bar forces the upper end of the lever 77 against the universal bar and trips the escapement. The space lever 77 is supported by the stationary frame or part 10 while the universal bar is mounted on the movable frame or part 11, the arrangement of the parts being such that when the machine is collapsed the upper end of the space lever does not project above the plane of the upper part of the platen. The space lever 77 and the parts connecting it to the 80 segment and space bar are omitted from Fig. 1, where they would naturally appear, in order not to complicate the figure and obscure other parts thereof. As indicated by the curved line $y-y$ Fig. 1, when the machine is collapsed the universal bar 61 moves downwardly at the rear of the shift frame and segment without interference.

The carriage escapement comprises a toothed wheel 78 and the lever or dog carrier 70 which is connected to the upper end of the link 69 whereby it is operated by the universal bar. The escapement is located directly in the rear of the platen and under the paper table, shown at 79, and the escapement wheel is arranged in front of the feed pinion 80 with the bearing for the escapement wheel and feed pinion located between these parts, said pinion 80 meshing with the feed rack 80° mounted on the carriage in any desired way. The bearing for the escapement wheel and pinion consists of a shouldered sleeve 81 screwed into a hole in the bracket 67 and having a central rib forming a double ball race for two annular 110 rows of balls. The escapement wheel has a conical central hole seated on the cone head of a shaft 82 and is locked thereto by screwing an inner cone 83 up against the wheel. The opposing cone is formed integrally 115 with the feed pinion 80 and this cone and pinion are locked to the shaft by a jam nut and washer or other securing means. A bearing of any other suitable sort for the escapement wheel and feed pinion could be 120 employed. The escapement lever or dog carrier is located over the escapement wheel and is loosely mounted on its pivot 84 to have a limited lengthwise movement, a slot 85 being provided for this purpose. 125

The lever or dog carrier 70 has a tooth or dog 85 adapted normally to engage the teeth of the wheel 78 and a tooth or dog 86 which acts to prevent the wheel 78 from moving a greater distance than a single tooth. Figs. 4 and 8 show the lever 70 in holding position with the lever forced to the left (right as seen in Fig. 4) and as soon as the dog 85 of the lever or dog carrier is released from the tooth of the escapement wheel a spring 87 acts to draw the lever to the right and the dog or tooth 86 is moved into position to engage a tooth of said wheel. The object of this spring and lengthwise movement of the lever 70 is to guard against the reengagement of the lever with the same tooth of the wheel before the carriage driving spring has overcome the inertia of the carriage and started the escapement wheel, as might happen in case a very light tensioned driving spring was used.

It will thus be evident that the platen carriage, escapement mechanism and universal bar are completely separated from the type action, and that in the collapsing or extensible condition of the machine no separation or disconnection of any kind is required between the universal bar and the escapement mechanism. It is further evident that the escapement mechanism, platen carriage and the parts directly connected to the escapement mechanism for operating the same are all mounted upon a movable main frame part relatively to the key and type action, which is mounted upon another main frame part; and that while the frame parts are shown hinged together, and certain parts mounted upon one frame part and other parts mounted upon another frame part, such arrangement, while desirable, is not necessarily essential, and the frame parts, instead of being hinged together, may either one of them be relatively movable in other directions instead of up and down, by reason of the hinged connection.

While a special form of type action, case shift, and other parts are shown, such parts are not specifically claimed herein as they form no part of the present invention, and it will be understood that suitable ribbon mechanism and other parts usually co-operating with the platen and carriage and common to typewriting machines are employed, such parts are neither shown nor claimed herein, as the present invention has reference more particularly to the escapement mechanism and the construction, mounting and combination of such mechanism and the feed mechanism generally with other parts of a writing machine.

Having thus described my invention, I claim as new and desire to secure by Letters Patent:

1. In a visible typewriting machine, the

combination of a universal keyboard, type operated by individual keys forming a part of the keyboard, a support, a carriage adapted to move along said support, a tension drum tending normally to force the carriage 70 along the support, escapement mechanism including a rack, a pinion, a toothed wheel, a dog carrying lever, all mounted upon the support and adapted with the support and carriage to be moved from a normal operative position to an inoperative and more compact one at the rear of the type, and a universal bar operatively connected to the dog carrier and mounted upon the support to partake of the compact movement of said support and the carriage.

2. In a visible typewriting machine, the combination of a universal keyboard, type-bars operated by individual keys forming a part of the keyboard, a support, a platen 85 carriage adapted to move along said support, a tension drum tending normally to force the carriage along the support, escapement mechanism including a rack, a pinion, a toothed wheel, a dog carrying lever, all 90 mounted upon the support and adapted with the support and platen carriage to be moved from a normal operative position to an inoperative and more compact one at the rear of the type-bars, and a universal bar adapted 95 to be moved by the type-bars and operatively connected to the dog-carrier and mounted upon the support to partake of the compact movement of said support and the platen carriage.

3. In a visible typewriting machine, the combination of a type action, including a universal keyboard having keys to operate individual type, a platen carriage foldable from a normal operative position to a more 105 compact and inoperative one, tension means for the carriage, a toothed wheel, a dog carrier having means to engage the toothed wheel, a pinion, a rack engaged by said pinion, a universal bar adapted to be moved 110 during the movement of the type while printing, arms connected to the universal bar, and links connecting said arms to the dog carrier, all mounted to partake of the compact movement of the carriage.

4. In a compactible typewriting machine, the combination of a two-part support, one part constituting a base frame member and the other being pivoted to the base frame member and normally extending upwardly 120 above the rear part of the base member, a platen carriage, a platen, a rack, a feed pinion, a rotary escapement wheel, a controlling pawl for said escapement wheel, an operating element connected to said controlling pawl, all of said elements being mounted on the pivoted frame part, key actuated means mounted in the base frame part and adapted to engage the escapement operating element, the pivoted member of the sup- 125 130

porting frame being so secured to the base frame part as to be swung downwardly and rearwardly at the rear of the base frame part to make the machine more compact and
5 to be swung upwardly and forwardly to place the platen in printing position and to bring the operating element of the escape-
ment in position to be operated by the key

actuated means on the base frame part, the two supporting members maintaining the operative elements in their upright positions during the act of compacting as well as extending the machine.

This specification signed this 6th day of June A. D. 1916.

EMMET G. LATTA.
